UNITED STATES PATENT OFFICE.

CHARLES CARSTENS, OF DENVER, COLORADO.

DISH-WASHER.

No. 922,455.

Specification of Letters Patent.

Patented May 25, 1909.

Application filed June 24, 1908. Serial No. 440,079.

To all whom it may concern:

Be it known that I, CHARLES CARSTENS, citizen of the United States, residing at Denver, in the county of Denver and State of Colorado, have invented certain new and useful Improvements in Dish-Washers, of which the following is a specification.

This invention is a dish-washing apparatus characterized particularly by improvement 10 with respect to a sprinkling device and a rack arrangement for holding the dishes to be washed. The construction is such that the dishes can be readily placed in or removed from the washer, and the apparatus 15 is sanitary, having no inaccessible corners or places for the accumulation of dirt.

The apparatus is illustrated in the accompanying drawings, in which—

Figure 1 is a front elevation, with the 20 doors of the casing or cabinet removed. Fig. 2 is a vertical section on line 2—2 of Fig. 1, with the doors in place. Fig. 3 is a detail of a traveling nut for operating the sprinkler.

25 Referring specifically to the drawings, *a* indicates an upright cabinet or casing lined with galvanized sheet metal and provided at the front with doors *a'* which have extended hinges as at *a''*, at the sides of the 30 cabinet, to open out of the operator's way. Within the upper part of the casing are racks *b*, formed of spiral springs, for holding plates and such flat dishes in upright and separate 35 position. These springs are fastened to the ends of the cabinet by means of clamps *e*, and are supported by cross rods *f* thereunder.

Racks *g* made from galvanized wire screens bent zigzag, as shown for receiving 40 cups, tumblers, combs etc., are fastened similarly at the ends of the cabinet and located in somewhat inclined position inwardly.

Hot water is forced upon the dishes, by 45 the traveling pipe sprinkler *h* with branch arms *h'* located closely under and beside the racks. The pipes are fitted with nozzles *i* which allow of better adjustment and direction of the water spray and protect the openings from excessive wear, and the nozzles can be flattened with a hammer or pliers to suit the water pressure.

The sprinkler is carried by a traveling nut *j*, being fastened thereto with clamps *k*. Nut *j* is a split cylinder with a loose follower nut *e* fitting a bore for the same. The nut has a

projection *e'* engaging the thread of screw *m*, which revolves in bearings *n* on top of the cabinet. The screw *m* has both right and left hand threads of steep pitch which meet 60 and unite at the ends in loops *o*, giving the sprinkler *h* a reciprocating motion traveling back and forth over the dishes a sufficient number of times to clean the dishes. The screw *m* is driven by pulley or flexible shaft 65 from a small motor.

In front of the cabinet is a tank *q*, for cold water, and for holding dishes ready for cleaning. Overflow from this tank goes into cabinet through hole *r* and drains at bottom of 70 machine into a large bowl *s* with removable strainer *t* for accumulating grease and preventing same from clogging up the drain and sewer pipe.

In use, the dishes are placed in or upon the 75 racks as described and the doors of the cabinet are closed. The screw is started and hot water turned on, causing the sprinkler to travel back and forth across the cabinet and spray and wash the dishes.

80 Various modifications may be made in the construction of the apparatus, within the scope of the invention, particularly with respect to the location of the racks and the 85 sprinkling pipes.

It is to be particularly noticed that there is great economy of water, as the sprinkler acts on only a few dishes at a time, as it travels back and forth, instead of on all the dishes in the cabinet. Hence the pressure of 90 an ordinary city water main will be sufficient to discharge the water with the necessary force to dislodge the dirt from the dishes, whereas if the sprinkler discharges over the 95 whole cabinet at once, additional pressure would have to be supplied from some source of power. This is an important feature under conditions where water under high pressure can not be obtained.

100 I claim:

1. A dish-washer comprising a cabinet having dish racks therein, and a sprinkling pipe movable back and forth across the cabinet and having branches projecting between the racks and jet openings directed toward said racks.

105 2. A dish-washer comprising a cabinet having openable doors at the front and a slot at the top having dish racks therein, a pipe depending through the slot and within the 110 cabinet beside the racks and having branches extending adjacent to said racks and pro-

vided with nozzles directed toward the same, and means to support the pipe and to reciprocate the same laterally in the slot and cabinet.

5. 3. A dish-washer comprising a cabinet having dish racks therein, an endless reversing screw extending across the cabinet, a traveling nut on the screw, and a spraying

pipe arranged to spray dishes on the racks and fastened to and carried by the nut.

In testimony whereof I affix my signature in presence of two witnesses.

CHARLES CARSTENS.
